United States Patent Office.

SAMUEL J. REEVES, OF PHILADELPHIA, PENNSYLVANIA.

Letters Patent No. 90,023, dated May 11, 1869.

IMPROVED RAILWAY-RAIL.

The Schedule referred to in these Letters Patent and making part of the same.

To all whom it may concern:

Be it known that I, SAMUEL J. REEVES, of Philadelphia, in the county of Philadelphia, State of Pennsylvania, have invented a new and continuous permanent Base for Rails on Railroads; and I do hereby declare that the following is a full and exact description thereof, reference being had to the accompanying drawings.

The nature of my invention consists in an improved mode of constructing a continuous base for rails, formed of three parts, each about the same length of the rail, but breaking joint with each other, so arranged as to receive the ordinary rails used on railroads, which will enable me to reduce materially the weight of the same, and to make it of a harder and more resisting material, and also, by the particular formation of the parts, comprising the base, will form a continuous bearing, with sufficient elasticity to the rail, without deflection, and, at the same time, in case of fracture of the rail, it is always held firmly to its place, without endangering the passing train. In combination with the rail, it also forms a continuous track, with nearly double the width of bearing-surface on the cross-ties of that obtained from the ordinary rail as now used.

In order to enable others skilled in the art to make and apply my invention, I will proceed to describe its construction and operation.

Figure 1 represents an elevation.

Figure 2, a cross-section, exhibiting all the parts in relative position.

Figure 3, a horizontal section.

In fig. 2, A represents a part or end of a rail of common form, with flanges *a a*.

B is a ribbed bar, of the same width at bottom as the base of the rail A, with ribs *b b*, on which the rail rests.

D D are supporting clamp-bars, each with a lip, *d*, overlapping the rail-flanges *a a* their entire length, and also with a double flange *e e* at the bottom of

each supporting clamp-bar D D, to rest upon the cross-ties, and which may be fastened to them in the usual way, by securing the outer flanges *e e*, while the inner flanges *e e* rest under and support the ribbed bar B its entire length.

The whole is firmly fastened together, with the alignment perfect, and made as one rail by the bolts E E, or other fastenings, passing through the supporting-clamps, and through slots made in the ribs *b b*, in the ribbed bar B, thus securely fastening the rail upon the ribbed bar, while the whole rests upon the cross-ties, with a base of about six inches.

By this arrangement, there is no danger of breaking the rail, as the supporting clamp-bars help to sustain the load, and relieve the rail from tensile strain; therefore, a much smaller rail may be used, of very hard iron or steel, made with particular reference to its capability to resist abrasion and crushing.

The ribbed bar may have one or more ribs, though two are preferable, and so arranged that neither shall be directly in a line with the stem of the rail, thus securing elasticity to the rail without increasing its deflection; and the ends of the rails are made as firm and permanent as any other part, and cannot sink under the weight of the train, being held in perfect alignment by the base with which it breaks joint, so that there are always three solid supporting-pieces under every rail-joint.

I claim as my invention, and desire to secure by Letters Patent—

The supporting clamp-bars D D, with the flanges *e e*, combined with the ribbed bar B, constructed as described, and the whole adapted to the ordinary rail A, substantially as herein set forth.

SAM'L. J. REEVES.
